US00D799636S

(12) **United States Design Patent** (10) **Patent No.:** **US D799,636 S**
Kimura et al. (45) **Date of Patent:** **** Oct. 10, 2017**

(54) **WATER PURIFIER**

(71) Applicant: **Mitsubishi Rayon Cleansui Co., Ltd.**,
Shinagawa-ku, Tokyo (JP)

(72) Inventors: **Shouzou Kimura**, Tokyo (JP); **Noboru Odamaki**, Tokyo (JP); **Tamotsu Matsumoto**, Chiba (JP); **Makiko Kida**, Chiba (JP); **Yelem Song**, Chiba (JP)

(73) Assignee: **Mitsubishi Rayon Cleansui Co., Ltd.** (JP)

(**) Term: **15 Years**

(21) Appl. No.: **29/562,868**

(22) Filed: **Apr. 29, 2016**

(30) **Foreign Application Priority Data**

Oct. 30, 2015 (JP) 2015-024378

(51) **LOC (10) Cl.** **23-01**

(52) **U.S. Cl.**

USPC **D23/207**

(58) **Field of Classification Search**

USPC D23/207, 209; 215/384; D7/316, 318, D7/319, 397, 612, 629; D9/530; 210/435, 244

CPC B01D 35/30; B01D 35/153; C02F 1/003; B65D 23/102

(57) **CLAIM**

The ornamental design for a water purifier, as shown and described.

DESCRIPTION

FIG. 1 is a perspective view of a water purifier showing our new design;

FIG. 2 is a front elevational view thereof; the rear elevational view is a mirror image of the front elevational view;

FIG. 3 is a left side elevational view thereof;

FIG. 4 is a right side elevational view thereof;

FIG. 5 is a top plan view thereof; and,

FIG. 6 is a bottom plan view thereof.

The broken lines shown in the drawings are for illustrative purposes only and form no part of the claimed design.

1 Claim, 4 Drawing Sheets
